(57) **CLAIM**

The ornamental design for a massaging device as shown and described.

DESCRIPTION

FIG. 1 is a top front, right side isometric view of a massaging device showing my new design;

FIG. 2 is a top rear, right side isometric view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The portion of the massaging device depicted in the figures in broken lines forms no part of the claimed design.
